TICKET OR CHECK ISSUING MACHINE

Reuben Harry Helsel, Long Island City, N. Y., assignor to General Register Corporation, Brooklyn, N. Y., a corporation of Pennsylvania

Application June 30, 1932. Serial No. 620,092

4 Claims. (Cl. 101—66)

This invention relates to ticket or check issuing machines.

More particularly stated the invention relates to a machine especially adapted for issuing tickets or checks for parking spaces, beaches or like uses. It is desirable that such tickets be dated and that one ticket only shall be issued for each operation of the machine.

One of the objects of the invention is to provide a ticket issuing machine of the character specified that is simple in construction and is so constructed and arranged that the feeding mechanism is positively controlled in a manner to prevent the issuance of more than one ticket 15 for each operation of the machine.

Another object of the invention is to provide a simple machine of the character specified that will stamp each ticket as it is issued with a date, number or other information.

20 Further objects of the invention will appear from the following specification taken in connection with the drawings which form a part of this application, and in which

Fig. 1 is a vertical sectional elevation of the 25 machine constructed in accordance with the invention;

Fig. 2 is a sectional elevation taken substantially on line 2, 2 of Fig. 1;

Fig. 3 is a detail elevational view showing the 30 operating means for the cutter; and

Fig. 4 is a plan view of the ticket.

The invention briefly described consists of a manually operable machine for feeding a strip of tickets a distance equal to the length of one 35 ticket for each operation thereof, the machine having means operable after the ticket has been fed for cutting the ticket from the strip and, furthermore, having means for stamping a date or other desired information on the ticket issued.

40 The machine is so constructed and arranged that the feed wheel can move for each feeding operation thereof a distance equal to the length of one ticket and will be positively locked against further feeding movement until the next operation 45 thereof.

Further details of the invention will appear from the following description.

In the particular embodiment of the invention illustrated in the drawings there is shown a machine comprising a casing 10 having a platform or table 11 on which the ticket is issued through a discharge opening 12.

The issuance of a ticket from the machine is controlled by a shaft S having fixed thereon cams 55 13, 14 and 15. The rotation of the shaft is lim-

ited by a fixed pin 20 which is disposed in a notch 21 in the cam 15.

In operating the machine the shaft S is oscillated by a crank 22 fixed to one end of the shaft and having a crank handle 23 thereon. The 60 shaft is actuated in a clockwise direction viewing Fig. 1 to feed the tickets and is returned to its initial position by means of a spring 25 secured at one end 26 to the shaft and having its opposite end 27 fixed against movement. 65

The tickets are preferably made in the form shown in Fig. 4 and as shown are provided with a plurality of central openings or holes 28 between successive tickets in a strip.

The ticket strip is fed by a feed wheel 30 70 having a plurality of peripherally disposed pins 31 arranged to enter the openings 28 of the strip. The feed wheel 30 is fixed on a shaft 32 to which is also secured a disk 33 having a plurality of notches 34 in the periphery thereof. 75

When the feeding mechanism is at rest one of the notches 34 is engaged by a pawl 35 which is mounted on a fixed pivot 36 and is controlled by a link 37 normally actuated in an upward direction by a spring 38. The cam 13 has a pin 40 projecting laterally therefrom and arranged to engage the upper end of the link 37 as the crank 22 and shaft S are rotated in a clockwise direction viewing Fig. 1. The engagement of the pin 40 with the link 37 will depress the pawl 35 and release the pawl from the notch 34. 80 85

The operation or rotation of the feed wheel is accomplished by means of the following mechanism. A rack 45 is slidably mounted on a frame 46 in the machine and has at its lower end rack teeth 47 which engage teeth 48 on a quadrant which is carried by or formed on an arm 49 rotatably mounted on the shaft 32. The arm 49 has pivotally mounted on its outer end a pawl 50 having a tooth 51 arranged to engage one of the notches 34 and a tail 52 on the opposite end thereof. The pawl is actuated in a direction to enter the notch by means of a spring 53. 90 95

The rack bar 45 has a roller 55 at its upper end which engages the cam 13. As the arm 22 is moved in a clockwise direction the cam 13 will depress the roller 55 and rack bar 45, thus causing the arm 49 to be swung in a clockwise direction. Since the pawl 50 engages one of the notches 34 in the disk 33 the disk will also be rotated in a clockwise direction and being fixed to the shaft 32 will cause the shaft and the feed wheel 30 to rotate in a direction to feed the ticket strip. A spring 56 engages the rack bar 45 and actuates the bar upwardly. 100 105 110

The locking and driving mechanism above described is so timed that upon the initial actuation of the crank arm 32 the pawl 35 will be depressed and released from one of the notches 34. Thereafter the further rotation of the crank arm and shaft will cause the rack bar 45 to be depressed, thus swinging the arm 49 in a clockwise direction and through the pawl 50 causing the disk 33 to rotate. Since this disk is fixed on the shaft 32 the feed wheel 30 will also be rotated.

After one length of ticket has been fed during one feeding movement of the arm 22 the pawl 35 will snap into the next notch succeeding the one from which it was released and will positively prevent further rotation of the feed wheel. At the same time the pawl 50 will be released from the notch it has engaged during the feeding movement and will be returned to the position shown in Fig. 1 by the action of the spring 56 on the rack bar 45. This is accomplished in the following manner: When the pawl 50 and arm 49 have completed their feeding movement these parts will be positioned in the location shown in dotted lines in Fig. 1. It will be noticed that the tail 52 of the pawl is disposed beneath a lug 60 on the lower end of a bar 61 which is slidably mounted on a pin 62, the pin being disposed in a slot 63 formed in the bar. The bar 61 is also mounted between stops or rollers 64 and can have a limited pivoted movement about the pin 62. A spring 66 holds the bar 61 elevated.

The cam 13 has a tail 70 which is adapted to engage a lug 71 on the upper end of the arm 61. When the pawl 50 has completed its feeding movement the tail 51 of the pawl will be disposed beneath the lug 60 on the arm 61. Upon the completion of the feeding movement of the shaft S the tail 70 of the cam 13 will swing the arm 61 about its pivot 62 until the tail 70 is disposed above the lug 71. Upon the release of the arm 22 the spring 25 will return the arm and shaft to their initial position and this movement will cause the tail 70 to depress the arm 61 and at the same time the lug 60 will release the pawl from the notch 34 and permit the arm 49 and pawl to return to the position shown in full lines in Fig. 1.

Means is provided for depressing a stamp roller on a ticket after the ticket has been fed from the machine and for impressing or printing thereon a date or other desired information.

In Fig. 1 there is shown a dating stamp D of any well known construction having a roller 75. The dating stamp has a lug 76 extending rearwardly therefrom and positioned for engagement by one end 77 of a lever arm 78 which is mounted on a fixed pivot 79 and carries intermediate its ends a roller 80. The roller 80 is operated by the cam 14 to depress the lever and stamp after each ticket has been fed from the machine to the table 11.

Means is also provided for severing the ticket from the strip after it has been fed. This means comprises a stationary knife blade 81 and a pair of pivoted knives 82 and 83. The knives 82 and 83 are engaged by links 84 having slots 85 in the upper end thereof. A lever 86 has an outer reduced end 87 positioned in each of the slots 85. The rear ends 88 of the levers 86 are positioned in the path of pins 90 formed on the cams 13 and 15. As these pins engage the levers 86 the knives 82 and 83 will be elevated, thus severing a ticket from the strip.

The ticket wheel 30 has secured thereto a gear

95 which is connected by gears 96 and 97 to a counter C which records the number of tickets issued from the machine.

From the foregoing description it will be seen that a simple, practical and efficient machine has been designed for feeding tickets one at a time from a ticket issuing machine and for positively preventing more than one ticket from being withdrawn for each operation of the machine. The machine, furthermore, includes a stamp for stamping on each ticket a date or other desired information.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A ticket issuing and stamping machine comprising manually operable rotatable means for feeding a strip of tickets one ticket length for each operation thereof, means for positively controlling said feeding means to limit the rotating feeding movement thereof to one length of ticket for one operation of said manual means, a printing device, means for operating the printing device after the ticket has been fed, and means for severing the ticket from the strip. 100

2. A ticket issuing and stamping machine comprising a manually operable feed wheel for feeding a strip of tickets one ticket length for each operation thereof, pawl means for positively controlling said feeding wheel to limit the feeding movement thereof to one length of ticket for one operation of said manual means, a printing device, means for operating the printing device after the ticket has been fed, and means 110 for severing the ticket from the strip. 115

3. A ticket issuing and stamping machine comprising manually operable means for feeding a strip of tickets one ticket length for each operation thereof, said means including a feed wheel, a disk connected thereto and movable therewith and having a plurality of notches, a feed pawl movable relative to the disk and engageable successively with said notches, a locking pawl engageable with said notches, means controlled by said manually operable feeding means for releasing the locking pawl, means controlled by said feeding means for moving the feed pawl through a predetermined arc to cause the feed wheel to feed the strip one ticket length, 120 means for releasing the feeding pawl and returning said pawl to its initial position after the strip has been fed. 125

4. A ticket issuing and stamping machine comprising manually operable means for feeding a strip of tickets one ticket length for each operation thereof, said feeding mechanism comprising a feed wheel, a notched disk connected thereto, a pawl engageable with the notches in the disk, means for moving said pawl through 130 an arcuate path including a rack and pinion and a cam for operating the rack, said cam being rotated by the manually operable feed means, and cam controlled means for releasing the feed pawl from a notch, upon the completion of the feeding movement, permitting the pawl to return to its initial position. 140 145
